UNITED STATES PATENT OFFICE.

DANA E. HARDING, OF ARLINGTON, MASSACHUSETTS, ASSIGNOR TO HARDING ENGINEERING COMPANY, OF BOSTON, MASSACHUSETTS, A CORPORATION OF MASSACHUSETTS.

SLICKING MACHINE.

Application filed August 8, 1925. Serial No. 48,946.

My present invention relates to the manufacture of leather from hides or skins, and more particularly to an improved apparatus for stretching and drying hides and skins during their treatment and preparation as leather.

At the present time this particular operation in the preparation of leather is performed manually, two men working preferably as a team, each with his own bench or table and the hides or skins are taken from a pile, dipped into a vat of glue or other mucilaginous substance by one man who uses one hide or skin and passes the other hide or skin to his team mate. The workman who takes the skin or hide from the vat of glue or other material, places the one retained by him, grain side down, on a board, preferably of cardboard, and by means of a slicking tool evens out the hide or skin and removes excess glue or other material from the hide or skin. The hide or skin after the evening or smoothing or, as it is called, slicking operation, is still wet, but the grain side of the hide or skin is brought into such close association with the smooth surface that it will remain in the position in which it is placed. The board, having thereon on one face the hide or skin, is flipped or turned over and passed in its turned over position to the second man of the team who places the same on his bench or table with the skin or hide thereon on the under side. The first man of the team passes to the second man of the team a skin or hide which he proceeds to even or slick onto the unoccupied surface of the board, after which he takes the board and hangs it on hooks on a travelling railway which carries it to the drying room. The slicking operation as now performed is relatively slow and it is extremely difficult to get two men to work together as a team and continuously as any indisposition of one of the members of the team slows down the work of the other member. The logical development in this art is from manual labor to machine work, and in my present invention I have devised a machine for smoothing or slicking out a hide or skin on a board, the slicking operation being performed mechanically and at a much greater speed than is possible by hand work and, further, the resulting work is more uniform in character. In practicing my improved inven-

tion, I slick the skin in all directions from the center of the skin outwardly and I find that such a working of the skin results in a hide or skin of greater surface area than is possible by any hand method, this being due to more even and uniform pressure imparted over the whole area of the skin or hide.

The principal object of my invention, therefore, is an improved apparatus forslicking skins or hides in the manufacture of leather.

Another object of my invention is an improved means for wiping out skins in two opposite radial directions simultaneously.

Other objects and novel features of the construction and arrangement of parts comprising my invention will appear as the description of the invention progresses.

In the accompanying drawings illustrating the preferred embodiment of my invention,

Fig. 1 is a side elevation;

Fig. 2 is an enlarged side elevation of a portion of the machine, portions thereof being shown in section;

Fig. 3 is a plan view of Fig. 1;

Fig. 4 is a sectional plan view on the line 4—4 of Fig. 1, and

Fig. 5 is a sectional plan view on the line 5—5 of Fig. 1.

Referring to the drawings, there is shown a worktable or bench comprising a plurality of legs 10 having secured on the top thereof a platform 11 and under the platform and to the upper portion of the legs 10 are secured the usual rails 12. This platform 11 is of any desired dimensions, but should be large enough to take the usual sized commercial board 13 which is ordinarily 5' 4" square. This board, as stated above, is 5' 4" square with the corners rounded and is about $\frac{1}{8}$ " thick. Its surface is covered with varnish or shellac and the edges are taped to prevent undue wear. Secured to the upper surface of the platform 11 about midway the length thereof by bolts 14 is a shallow U-shaped member 15 and formed integral with such U-shaped member and extending upwardly therefrom and centrally thereof is a second U-shaped member 16.

Formed in the U-shaped members 15 and 16 and in vertical alignment with each other are bearings in which is slidably

mounted the sleeve 17. Formed integral with the sleeve 17 and above the U-shaped member 15 is a hub 18 in which is formed an annular groove 19. Pivotally mounted 5 on the shaft 20 in the U-shaped member 16 is a lever 21, this lever being forked at one end and in the forked end are inwardly extending stub shafts 22. On the inner end of the stub shaft 22 are rotatably mounted 10 rollers 23 which fit within the annular groove 19. The lever 21 extends inwardly of the machine and terminates in a handle 24 which handle is adapted to engage with the catch or stop 25 secured to the U-shaped 15 member 15 by screws 26. When the handle portion 24 engages with the stop or catch 25, the rollers 23, engaging with the sides of the annular groove 19, will move the sleeve 17 to its uppermost position, as viewed in 20 Fig. 1. This lever 21 is provided with devices which will be hereinafter described. The lower end of the sleeve 17 has formed integral therewith a flange 27, and secured to the under face of the flange 27 by bolts 25 28 is a hollow rectangular framework 29, this framework being of any desired width and of a length to swing radially between the downwardly extending portions of the U-shaped member 15. 30 The rectangular frame 29 is provided with parallelly arranged radially mounted shafts 30, these shafts being arranged in pairs on either side of the center of the framework and on each shaft is secured a 35 roller 31 of any suitable diameter, the rollers 31 being, of course, equal to each other in diameter. Over each pair of rollers runs an endless flexible belt 32 of rubber, canvas, or any other suitable material. Secured to 40 each endless belt 32 at intervals along the length thereof and parallel to each other are slicking tools 33 and the number of tools 33 may be any desired. By reference to Fig. 2 it will be noted that the manner in 45 which the slicking tools 33 are secured to the endless belts 32 is such that a minimum of wear is placed on the endless belts 32 as such belts move over the rollers 31. Rotatably mounted in suitable bearings in the 50 rectangular framework 29 centrally with respect thereto and parallel to the shafts 30 are stub shafts 34 and 35 respectively. Secured to the outer end of the shaft 34 is a gear 36 that meshes with and drives a similar gear 37 secured to the adjacent end of the shaft 30 immediately to the left thereof, as viewed in Figs. 1, 2 and 3. Secured to the 55 inner end of such shaft 34 is a bevel gear (not shown) that meshes with and is driven by a bevel pinion 38. Secured to the outer end of the shaft 35 is a gear 39 that meshes with and drives a similar gear 40 secured to the adjacent end of the shaft 30 immediately to the right thereof, as viewed in the 60 figures. Secured to the inner end of the 65 shaft 35 is a bevel gear 41 that meshes with, and is driven by, the bevel pinion 38. The bevel gear on the inner end of the shaft 34 and the bevel gear 41 on the inner end of the shaft 35 are equal in diameter and pitch, 70 also the gears 36, 37, 39 and 40 are equal in pitch and diameter and therefore it will be obvious that the right and left hand shafts 30 immediately adjacent to the shafts 34 and 35 and, therefore, the endless belts 32, 75 will be driven at the same speed. The bevel pinion 38 is secured to a shaft 42 that is rotatably mounted in the sleeve 17 above described. The shaft 42 extends upwardly beyond the limit of the U-shaped member 80 16 and has mounted on its top end a bevel gear 43 that meshes with and is driven by a bevel pinion 44 secured to a shaft 45 rotatably mounted in a bearing member 46 formed integral with, and at the upper end 85 of, the U-shaped member 16. The upper end of the shaft 42 is splined, as shown in Fig. 1, and the connection between the shaft 42 and gear 43 is such that the gear 43 rotates with the shaft 42, but is capable of 90 relative longitudinal movement thereon. Secured to the shaft 45 intermediate the ends thereof is a worm wheel 47 that meshes with and is driven by a worm 48 secured to the driving shaft of a motor 49, and such 95 motor being secured to a platform 50 formed integral with, and extending outward from, the U-shaped member 16. 100 Formed in the end of the member 46 and on the U-shaped member 15 are bearings in which is mounted for vertical rotative movement a shaft 51. Secured to the shaft 51 adjacent to the upper end thereof is a worm wheel 52 that meshes with and is driven by the worm 48 above described as being 105 secured to the driving shaft of the motor 49. Secured to the shaft 51 intermediate its ends is a cam disc 53 that has secured to one face thereof a cam 54. Formed on the lever 21 intermediate the ends thereof 110 is a member 55 in which is secured a shaft 56 and on this shaft 56 is rotatably mounted a roller 57 that is adapted to engage with the cam 54, this construction enabling the vertical movement of the sleeve 17 and attached parts to take place automatically and mechanically. Adjustably secured to the lever 21 adjacent to the handle portion 24 is a weight 58, this weight being useful 115 where the lever 21 is to be manually operated. 120 Formed integral with the sleeve 17 above the member 18 is a circular ratchet 59 adapted to be engaged by a pawl 60 pivotally attached to one end of a lever 61. The lever 61 is pivotally mounted intermediate its ends on a shaft 62 secured to legs or pins 63 that are formed integral with and extend laterally outward from the U-shaped member 16. The end of the lever 61 remote from the 125 130

pawl 60 is forked, as indicated at 64, and in such forked end is rotatably mounted a roller 65 adapted to engage with the cam disc 53. The cam disc 53 in its rotation with the shaft 51 will cause a rotary step by step movement of the disc 59 and, therefore, the sleeve 17 and all parts attached thereto, this rotary step by step movement being independent of the shaft 42 and attached parts.

The lower end of the shaft 42 is counterbored to receive a longitudinally slidable shaft 66. To the lower end of the shaft 66 is secured a hub 67 that has formed integral therewith or attached thereto a disc 68 of any suitable diameter. Secured to the shaft 66 intermediate its ends is a collar 69 and between the upper end of the collar and the bottom of the counterbored portion 20 of such shaft 42 is a coil spring 70. The coil spring 70 tends to force the shaft 66, hub 67, and disc 68 downwardly, as viewed in the drawings and particularly in Fig. 2, and such downward movement is limited by the 25 screw 71 threaded through a hole in the shaft 42.

The operation of my improved apparatus is as follows, it being understood that such apparatus may be operated in its entirety to 30 perform the complete operation of placing a hide or skin on both sides of a card 13 or may be utilized as one piece of apparatus where team work between two workmen is relied upon to completely fill such card or 35 board with a hide or skin. Assuming that it is desired to place the apparatus in service, the operator will push down on the handle 24 until it is engaged by the stop or catch 25, such downward motion causing an upward movement of the rectangular framework 29 and all parts carried thereby as 40 well as an upward movement of the disc 68 which moves, therefore, from clear of the platform or table top 11. A board, such as a shellacked or varnished sheet of card- 45 board, as 13, is placed on the top of the platform or table 11 and the operator either takes from the vat of glue or other material or dips into such a vat a hide or skin as 50 indicated by the numeral 72, such hide or skin being placed grain side downward onto the board 13. Power is turned into the motor 49 which thereupon causes a rotation of the shafts 42 and 51. The operator will now 55 release the handle portion 24 from the catch or stop 25, allowing such handle portion to move upwardly, thus allowing the rectangular framework 29 and all parts attached thereto to move downwardly or into the position shown in Fig. 1. Also, the shaft 42 is moved downwardly and the construction 60 is such that the disc 28 will engage with the central portion of the hide or skin 72 before theslicking tools 33 on the endless belts 32 can engage with the flush side of the hide 65

or skin. The shaft 42 rotating, will cause, as above described, a movement of the endless belts 32 in the direction of the arrow shown in Fig. 2, thus causing a smoothing action of the slicking tools on the leather 70 radially outward on both sides of the centrally located shaft 42. The cam disc 53 with the cam 54 thereon will engage with the rollers 65 and 57 respectively. The engagement of the rollers 65 with the cam disc 75 53 will cause an intermittently rotative movement of the sleeve 17 and, therefore, of the rectangular framework 29 about the shaft 42 as a center. Periodically, also, the cam 54, engaging with the roller 57, will 80 cause a movement of the lever 21 about its pivot shafts 20, thus moving the sleeve 17 and all parts attached thereto upward and downward. The cam disc 53 and cam 54 are so arranged with respect to the levers 21 85 and 61 that the rotative movement of the sleeve 17 bears a certain relation to the upward and downward movement thereof, this relation being such that the rotative movement of the sleeve 17 taking place only when 90 such sleeve is in its upper position and with the slicking tools 33 out of engagement with the hide or skin 72. It will be apparent that the sleeve 42 need only rotate one half revolution to have the hide or skin completely 95 put on or slicked onto a card 13, at the end of which half revolution the operator pushes down on the handle portion 24 of the lever 21, removes the card with the slicked hide or skin 72 thereon, and, if this is the first 100 hide or skin that has been put on, he turns the card 13 over, replaces it in the machine, and repeats the operation on another hide or skin. When both sides of the card or 105 board 13 have attached a hide or skin, the operator removes the board 13 and places it in a rack or ordinarily hangs it on a travelling conveyor which conveys the board and attached hides or skins to a drying apparatus (not shown).

While I have necessarily shown and described the preferred embodiment of my invention somewhat in detail, it is to be understood that I may vary the size, shape, and arrangement of parts within wide limits without departing from the spirit of the invention.

Having thus described my invention, what I claim as new is:

1. An improved apparatus for use in the treatment of hides and skins comprising a work support, a yieldingly held anvil for engaging and holding work on said support, and means operable to put out a hide or skin from the anvil in two opposite radial directions simultaneously.
2. An apparatus for use in the treatment of hides and skins comprising a work support, a yieldingly mounted anvil positioned above said support and adapted to hold 130

work in position on the work support, a rectangular framework associated with said anvil, smoothing devices on said rectangular framework, and means for operating said smoothing devices to smooth a hide or skin onto the work support from each side of the anvil simultaneously.

3. An apparatus for use in the treatment of hides and skins comprising a work support, a yieldingly mounted anvil positioned above said support and adapted to hold work in position on the work support, a rectangular framework associated with said anvil, a pair of endless belts mounted in said framework, smoothing devices mounted on said belts, and means for operating said smoothing devices to smooth a hide or skin onto the work support from each side of the anvil simultaneously.

20 4. An apparatus for use in the treatment of hides and skins comprising a work support, a yieldingly mounted anvil positioned above said support and adapted to hold work in position on the work support, a rectangular framework associated with said anvil, a pair of endless belts mounted in said framework, a plurality of smoothing devices mounted on said belts, and means for operating said smoothing devices to smooth a hide or skin onto the work support from each side of the anvil simultaneously.

35 5. An apparatus for use in the treatment of hides and skins, comprising a work support, a yieldingly mounted anvil positioned above said support and adapted to hold work in position on the work support, a rectangular framework associated with said anvil, a pair of endless belts mounted in said framework, a plurality of smoothing devices mounted on said belts and parallelly arranged with respect to each other, and means for operating said smoothing devices to smooth a hide or skin onto the work support from each side of the anvil simultaneously.

45 6. An apparatus for use in the treatment of hides and skins, comprising a work support, a yieldingly mounted anvil positioned above said support and adapted to hold work in position on the work support, a rectangular framework associated with said anvil, smoothing devices on said rectangular framework, means for operating said smoothing devices to smooth a hide or skin onto the work support from each side of the anvil simultaneously, and means for intermittently moving said smoothing devices into and out of engagement with the work.

60 7. An apparatus for use in the treatment of hides and skins, comprising a work support, a yieldingly mounted anvil positioned above said support and adapted to hold work in position on the work support, a rectangular framework associated with said anvil, smoothing devices on said rectangular framework for operating said smoothing de-

vices to smooth a hide or skin onto the work support from each side of the anvil simultaneously, and means for automatically and intermittently moving said smoothing devices into and out engagement with the work. 70

8. An apparatus for use in the treatment of hides and skins, comprising a work support, a yieldingly mounted anvil positioned above said support and adapted to hold work in position on the work support, a rectangular framework associated with said anvil, smoothing devices on said rectangular framework for operating said smoothing devices to smooth a hide or skin onto the work support from each side of the anvil simultaneously, and means for rotating said framework with respect to the work. 75 80

9. An apparatus for use in the treatment of hides and skins comprising a work support, a yieldingly mounted anvil positioned above said support and adapted to hold work in position on the work support, a rectangular framework associated with said anvil, smoothing devices associated with said anvil, and means for intermittently rotating said framework with respect to the work. 85 90

10. An apparatus for use in the treatment of hides and skins, comprising a work support, a yieldingly mounted anvil positioned above said support and adapted to hold work in position on the work support, a rectangular framework associated with said anvil, smoothing devices on said rectangular framework, means for operating said smoothing devices to smooth a hide or skin onto the work support from each side of the anvil simultaneously, means for moving said smoothing devices out of engagement with said work, and means for rotating said framework when the smoothing devices are out of engagement with the work. 95 100 105

11. An apparatus for use in the treatment of hides and skins, comprising a work support, a yieldingly mounted anvil positioned above said support and adapted to hold work in position on the work support, a rectangular framework associated with said anvil, smoothing devices on said rectangular framework, means for operating said smoothing devices to smooth a hide or skin onto the work support from each side of the anvil simultaneously, means for moving said smoothing devices out of engagement with said work, and means for rotating said framework by step by step movements when the smoothing devices are out of engagement with the work. 110 115 120

12. An apparatus for use in the treatment of hides and skins, comprising a work support, a yieldingly mounted anvil positioned above said support and adapted to hold work in position on the work support, a rectangular framework associated with said anvil, smoothing devices on said rectangular 125 130

framework, means for operating said smoothing devices to smooth a hide or skin onto the work support from each side of the anvil simultaneously, means for automatically moving said smoothing devices out of engagement with said work, and means for rotating said framework when the smoothing devices are out of engagement with the work.

10 13. An apparatus for use in the treatment of hides and skins, comprising a work support, a yieldingly mounted anvil positioned above said support and adapted to hold work in position on the work support, a rectangular framework associated with said anvil, smoothing devices on said rectangular framework, means for operating said smoothing devices to smooth a hide or skin onto the work support from each side of the anvil simultaneously, means for automatically moving said smoothing devices out of engagement with said work, and means for

rotating said framework by step by step movements when the smoothing devices are out of engagement with the work.

25

14. An apparatus for use in the treatment of hides and skins, comprising a work support, a yieldingly mounted anvil positioned above said support and adapted to hold work in position on the work support, a rectangular framework associated with said anvil, smoothing devices on said rectangular framework, means for operating said smoothing devices to smooth a hide or skin onto the work support from each side 30 of the anvil simultaneously, manually operable means for moving said smoothing devices out of engagement with said work, and means for rotating said framework 35 when the smoothing devices are out of engagement with said work.

40 In testimony whereof, I have signed my name to this specification.

DANA E. HARDING.
